PLASTIC FIGURED TEXTILE FABRIC

Reid C. Goodbar, Ware Shoals, and Richard N. James, Greenwood, S.C., assignors to Riegel Textile Corporation, a corporation of Delaware

Filed Apr. 4, 1966, Ser. No. 1,764

Term of patent 14 years

(Cl. 87—3)

We claim:

The ornamental design for a plastic figured textile fabric, as shown.
